DESIGN FOR A SUNSHADE

Thomas Pace and Cass T. Walker, San Jose,
Calif.

Application March 11, 1938, Serial No. 75,758

Term of patent 7 years

To all whom it may concern:

Be it known that we, Thomas Pace and Cass T. Walker, citizens of the United States, residing in the city of San Jose, county of Santa Clara, and State of California, have invented a new, original, and ornamental Design for a Sunshade, of which the following is a specification, reference being had to the accompanying drawing, forming a part thereof.

In the accompanying drawing:

Fig. 1 is a side elevational view of a sunshade showing our new design; and

Fig. 2 is a top plan of the same.

We claim:

The ornamental design for a sunshade substantially as shown.

THOMAS PACE,
CASS T. WALKER.
